THOMAS B. JORDAN, OF SOUTH LAMBETH, ENGLAND, ASSIGNOR
TO B. H. BARTOL, OF PHILADELPHIA, PENNSYLVANIA.

Letters Patent No. 83,505, dated October 27, 1868; patented in England, October 28, 1865.

IMPROVEMENT IN STEAM-GENERATORS.

The Schedule referred to in these Letters Patent and making part of the same.

To all whom it may concern:

Be it known that I, THOMAS B. JORDAN, of South Lambeth, London, England, have invented certain Improvements in Steam-Boilers, for which Letters Patent of the Kingdom of Great Britain and Ireland were granted to me on the 28th day of October, A. D. 1865; and I do hereby declare the following to be a full, clear, and exact description of the same.

My invention consists—

First, in the novel construction of a steam-boiler, the main body of which consists of vertical or inclined wrought-iron tubes.

Second, in a novel arrangement of the boiler with respect to the brick-work, with the view of obtaining a uniform distribution of heat to the vertical or inclined tubes.

In order to enable others skilled in the art to make and apply my invention, I will now proceed to describe its construction and operation, reference being had to the accompanying drawing, which forms a part of this specification, and in which—

Figure 1 is a vertical section of my improved steam-boiler, and

Figure 2 a sectional plan of the same.

The body of the boiler consists of any desired number of wrought-iron tubes, A, arranged in rows as seen in fig. 2. In the present instance these tubes are vertical, but if desired they may be inclined, and there are three rows, two containing three tubes, and an intermediate row of four tubes, but this arrangement may be modified in accordance with the size of the boiler.

The tubes of each row are so secured at their lower ends to a horizontal pipe, B, that there is a free communication between the latter and the said tubes A, which fit in sockets, a, the latter being fitted to flanges, b, on the horizontal pipes, and the whole being secured firmly together by bolts D, one bolt passing through each tube, the lower bent end or T-shaped head of the bolt bearing against the inside of the horizontal pipe, at a point adapted to receive it, and its upper end passing through a cap, d, fitted to the top of each vertical or inclined tube, above which cap the bolt is furnished with a suitable washer and nut.

At the upper end of the generator is a horizontal pipe, E, which may be termed the general steam-receiver and distributor, inasmuch as it is made to communicate with the tubes A, at the upper end of the same, through a series of small tubes e, in a manner which will be readily understood. This pipe E is furnished with a suitable safety-valve and with a shut-off valve through which steam is admitted to the engine.

The feeding of the boiler is effected through a tube, F, and the blowing off through a tube, F', which tubes

communicate with the horizontal pipes B B, in a manner readily understood by reference to the drawing.

Hitherto I have referred to the peculiar construction of the generator only. I will now proceed to describe another important feature of my invention, which is the arrangement of the boiler on the foundation.

It will be observed, on reference to fig. 1, that the horizontal pipes B and the sockets a, in which the vertical or inclined tubes A fit, are embedded in the brick-work foundation G, and are consequently protected from the direct action of the products of combustion of the fuel on the grate H of the fire-place I, to which action, however, the vertical or inclined tubes A are directly exposed, these tubes being contained in a rectangular chamber of brick-work, and this chamber terminating above at f, where the brick-work meets the caps d at the upper end of the tubes A.

K is the chimney, with which communicate three horizontal flues, L L' L", situated one above another, each of these flues being furnished with a damper, m, which can be operated readily from the outside of the brick-work. Each of these horizontal flues communicates, through any desired number of openings, n, with the chamber containing the generator.

It is highly important, in boilers of this class, that the joints, where a union is effected between vertical or inclined and horizontal tubes, should be protected from the direct action of the fire. This end is effectively accomplished by embedding the lower end of the generator in the brick-work which serves as the foundation, and this is done without any material loss of heating-surface. It is also important that the direction of the products of combustion from the chamber containing the generator should be changed, as circumstances may suggest.

Thus, should it be found that the products of combustion act too severely on the lower portion of the generator, the communication of the lowest horizontal flue L" might be cut off by closing its damper, or the dampers of the whole of the flues might be so regulated that a uniform dissemination of the products of combustion throughout the chamber containing the generator might be obtained, and every portion of the tubes A forming the water-space of the boiler thus exposed to a uniform heat.

I wish it to be understood that I do not desire to confine myself to any specific number of rows of tubes A, or to any determined number of flues arranged one above another, as the size of the boiler must determine these points; but

I claim as my invention, and desire to secure by Letters Patent—

1. The combination of the upright pipes E, hori-

zontal pipes B, and a steam-chest or reservoir, E, substantially as described.

2. A generator, constructed substantially as described, and having its lower portion embedded in the brick-work, substantially as set forth.

3. The combination, with a chamber containing a steam-generator, of two or more flues having independent dampers, substantially as set forth.

In testimony whereof, I have signed my name to this specification in the presence of two subscribing witnesses.

THOS. B. JORDAN.
